CLAIM

The ornamental design for a sole for footwear as shown and described.

DESCRIPTION

FIG. 1 is a perspective view of a sole for footwear showing my new design;

FIG. 2 is a front view thereof;

FIG. 3 is a back view thereof;

FIG. 4 is a right side view thereof;

FIG. 5 is a left side view thereof;

FIG. 6 is a top view thereof; and,

FIG. 7 is a bottom view thereof.

The broken line showing of a shoe in FIGS. 1–6 represents unclaimed environment. The broken lines in FIG. 7 illustrate portions of the sole for footwear that form no part of the claimed design.

1 Claim, 7 Drawing Sheets
